CLAIM

The ornamental design for a barbell plate, as shown and described.

DESCRIPTION

FIG. 1 is a front, right and bottom perspective view of a barbell plate, showing my design.

FIG. 2 is a rear, left and top perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is an enlarged view of detail 9 in FIG. 1; and,

FIG. 10 is a cross-sectional view of the barbell plate of FIG.

1, taken along section line 10-10 as depicted in FIG. 3. The broken lines depict portions of the barbell plate that form no part of the claimed design. The dot-dash broken lines in FIGS. 1 and 9 depict the boundaries of the enlargements that form no part of the claimed design.

1 Claim, 10 Drawing Sheets
